SMOKER'S PIPE

Walter H. Rasener, Indianapolis, Ind.

Application December 29, 1937, Serial No. 182,289

2 Claims. (Cl. 131—225)

The object of this invention is to provide a sanitary pipe which will transmit cool, dry smoke to the user, devoid of nicotine and other deleterious and disagreeable qualities.

A further object is to keep saliva from the mouth of the smoker from entering the bowl of the pipe and from contacting the tobacco, and another and important object is to collect the nicotine in a compartment of the pipe separate from that in which the tobacco is contained and consumed and to provide easy means for the removal of the nicotine and for the cleaning of the pipe.

I accomplish the above by the device illustrated in the accompanying drawing, in which:

Fig. 1 is a longitudinal vertical section of a pipe embodying my invention;

Fig. 2, a like view of the bowl-end of the pipe with the detachable inner bowl removed;

Fig. 3, a perspective view of the inner bowl tilted to disclose the lower portions;

Fig. 4, a cross section on the line 4—4 of Fig. 1; and

Fig. 5, a sectional view similar to Fig. 2 of a modified outer bowl.

Like characters of reference indicate like parts in the several views of the drawing.

The outer bowl 6 may be formed out of wood such as briarwood, or out of meerschaum, "Bakelite" or other composition. It has an integral stem extension 7 to which a mouth-piece 8 is removably attached, preferably and as shown in Fig. 1, by a joint formed by telescoping the reduced end 9 of the mouth-piece into a bore 10 of the extension 7. The mouth-piece will be of any usual and suitable material.

The outer bowl 6 has the central recess 11, which is open at the top and closed at the bottom. Suspended within the recess 11, from the upper edge or rim of the bowl 6, is an inner bowl 12, within which the tobacco is placed and burned. The inner bowl 12 has a top outside flange 13 that projects over and rests with a close fit upon the rim of the outer bowl, as shown in Fig. 1. The outside walls of the inner bowl at 14, preferably make a close fit with the bore of the outer bowl adjacent the under side of the flange in order to center the inner bowl, but below, and for the major length of the inner bowl, the outside diameter is reduced to provide a chamber 15 for the free circulation of heat, smoke and gaseous products of combustion around the inner bowl. This space is continued under the bottom of the bowl 12, as shown, and a hole 16, is formed in

the bottom of the inner bowl 11, for the discharge of smoke and vapors.

A passageway or port 17 is formed in the wall of the bowl 6, forming a communication from the chamber 15 into the bore 10 of the stem-extension 7. In the form illustrated, the wall of bowl 6 is thickened on the side next to the stem as shown in Fig. 4, to enable the passageway 17 to be obliquely formed as shown in Figs. 1 and 2, for easier cleaning.

The flange 13 is made to conform in shape with the rim of bowl 6, thereby requiring exactitude in its placement on the bowl. To insure this and also to draw the flange into a close fit on the pipe I provide bayonet joint channels 18, in the inner walls of the recess 11, on both sides, to receive lugs 19 formed on the walls 14 of the inner bowl. These have oblique channels which act as a screw thread to draw the flange toward the rim of the bowl, and the channels end with a short portion 20, parallel with the rim of the bowl and closed to stop the lugs 19 at the right place.

In the operation of my pipe, smoking tobacco is placed in the inner bowl 12, lighted and drawn upon through mouth-piece 8 in the usual manner. The resulting smoke and products of combustion, drawn out through hole 16, circulate all around the inner bowl in the chamber 15 and pass out through the passageway 17 to the bore 10, and mouth-piece 8, to the smoker's mouth. Nicotine and condensed moisture from the tobacco condense and remain at the bottom of the recess 11 in the outer bowl 6.

The recess 11 in the outer bowl is made accessible for cleaning by removing the inner bowl 12. Should passageway 17 and bore 10 become clogged or fouled a broom straw or small wire can be pushed through, after removing the inner bowl and mouthpiece 8.

In the modification shown in Fig. 5, the angles of the passageway 17 are replaced by curves to make the insertion of the wire easier.

While I have here shown and described my invention in the best form now known to me, it is obvious that many variations in form and in material out of which it is made are possible without departing from the spirit of the invention, and I therefore do not desire to be limited any more than is required by the following claims.

I claim:

1. In a pipe having an outer bowl with a central recess, a top rim and a hollow stem, the wall of the bowl being thickened next to the stem and having an inner bowl of less diameter than that

- of the recess, with a bottom discharge hole and having an outside flange at its top by which flange the inner bowl is suspended in the outer bowl from the rim of the outer bowl, and said inner bowl having a top spacing ring defining a smoke recess between the bowls, the outer bowl having a smoke passageway in its thickened wall leading from the upper part of the space between the two bowls and discharging into the bottom stem, a bayonet joint comprising a lug on the inner bowl and a channel in the wall of the outer bowl receiving the lug, the entrance of said channel being at right angles to the top of the bowl and leading into a downwardly oblique extension having a convex lower wall terminating with a short portion parallel with the top of the bowl against the end of which short portion the lug is arrested and its return movement resisted by the convex portion thereby normally locking the lugs.
- 5 2. In a pipe having an outer bowl with a central recess, a top rim and a hollow stem, the wall of the bowl being thickened next to the stem and having an inner bowl of less diameter than that
- 10 of the recess, with a bottom discharge hole and having an outside flange at its top by which the inner bowl is suspended in the outer bowl and registering in size and shape with the wall of the outer bowl, said inner bowl having a top spacing ring defining a smoke receiving recess between the bowls, the outer bowl having a smoke passageway in its thickened wall leading from the upper part of the space between the two bowls and discharging into the bottom stem, a bayonet joint comprising a lug on the inner bowl and a channel in the wall of the outer bowl receiving the lug, the entrance to said channel being at right angles to the top of the bowl and leading into a downwardly oblique extension having a convex lower wall terminating with a short portion parallel with the top of the bowl, against the end of which short portion the lug is arrested having the return movement resisted by the oblique convex lower wall thereby normally locking the lug, 15 when the flange of the inner bowl is in register with the rim of the outer bowl.
